US0D1086096S

(12) **United States Design Patent** (10) Patent No.: **US D1,086,096 S**
(45) Date of Patent: ** Jul. 29, 2025

(54) **WIRELESS SPEAKER**

(71) Applicant: **Yuyuan Zhang**, Guangdong (CN)
(72) Inventor: **Yuyuan Zhang**, Guangdong (CN)
(73) Assignee: **Shenzhen Kaiwu Muchuang Technology Co., Ltd.**, Shenzhen (CN)
(**) Term: **15 Years**
(21) Appl. No.: **29/885,032**
(22) Filed: **Feb. 17, 2023**

(30) **Foreign Application Priority Data**

(57) **CLAIM**

The ornamental design for a wireless speaker as shown and described.

DESCRIPTION

FIG. 1 is a perspective view of a wireless speaker showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a rear side perspective view thereof; and,

FIG. 9 is a right side perspective view thereof.

The broken lines in the drawings depict portions of the

wireless speaker that form no part of the claimed design.
